UNITED STATES PATENT OFFICE.

CHARLES M. HOFFMAN OF LEBANON, NEW HAMPSHIRE.

FAUCET.

1,147,943.

Specification of Letters Patent.

Patented July 27, 1915.

Application filed November 30, 1914. Serial No. 874,796.

To all whom it may concern:

Be it known that I, CHARLES M. HOFFMAN, a citizen of the United States, residing at Lebanon, in the county of Grafton and State of New Hampshire, have invented new and useful Improvements in Faucets, of which the following is a specification.

The invention relates to a faucet and more particularly to the class of duplex valve faucets.

The primary object of the invention is the provision of a faucet, wherein in addition to the ordinary hand operated stem valve for opening and closing the same, there is arranged an auxiliary valve, which is disposed rearwardly of the stem valve and is designed as a cut-off valve for use only when necessary to shut off the water to the faucet from the main, thus being of great convenience to plumbers or any one else when a new gasket is needed to stop leakage at the stem valve, as considerable time is saved by not having to go into the cellar to turn the water off or on, and at the same time leaving the water clear and clean of rust or grit when again turned on for use through the faucet.

Another object of the invention is the provision of a faucet wherein the water supply can be turned off at the same, to avoid the freezing of the water therein, during cold weather, or when the water is not constantly used through the faucet, thus in this manner the necessity of shutting off the supply at the main or at a remote point is obviated.

A further object of the invention is the provision of a faucet, wherein the cut off valve, in contradistinction to the hand stem valve, therein, is fitted with a lever, which is of novel form to engage with the casing of the faucet, so as to lock the said valve in open position for the free supply of water to the faucet, and also which can be sprung out of engagement with the casing to permit the valve to be closed, for shutting off the supply, the lever being of a contour to conform to the shape of the lower portion of the said casing, so as not to disfigure or detract from the appearance of the faucet.

A further object of the invention is the provision of a faucet, wherein the inconvenience ordinarily experienced in a house, when it is necessary for a person to go to the cellar for cutting off the water supply, is entirely eliminated, as the cut off of the

water may be effected at a convenient point in any of the upper stories of the house.

A still further object of the invention is the provision of a faucet, which is simple in construction, reliable and efficient in operation, and inexpensive in manufacture.

With these and other objects in view, the invention consists in the features of construction, combination and arrangement of parts as will be hereinafter fully described, illustrated in the accompanying drawing and pointed out in the claim hereunto appended.

In the drawing:—Figure 1, is a side elevation of a faucet constructed in accordance with the invention. Fig. 2, is a vertical sectional view. Fig. 3, is a sectional view on the line 3—3 of Fig. 1. Fig. 4, is a bottom plan view.

Similar reference characters indicate corresponding parts throughout the several views in the drawing.

Referring to the drawing, in detail the faucet comprises a casing 5, formed with a discharge spout 6, having external threads 7, 80 for the attachment of a hose or filter, as usual, while formed at the other end of the casing is an externally threaded nipple 8, and wrench engaging surfaces 9, for the connection of the faucet with a water pipe 85 of a supply system installed in a house or the like. The casing 5, is formed between its ends with closely arranged substantially spherical shaped portions 10 and 11, respectively, in which are located the duplex 90 valve mechanism, hereinafter fully described. In the portion 10 is located a reciprocating valve 12, of the ordinary well known construction, having a stem 13, fitted with a handle 14, as usual, while located in the portion 11, of the casing is an auxiliary cut off plug valve 15, which is disposed rearwardly of the said valve 12, and is only used to decrease the supply of water to the faucet or to entirely shut off the water therefrom to the main.

The valve 15, has secured to its larger end, which is located at the bottom of the casing 5, a resilient lever 16, which has the outwardly bowed portions 17 and 18, respectively, the same being correspondingly shaped to the contour of the bottom of the casing at the points opposite thereto, so that the said lever 16, will lie in close relation to the said casing, while the free end of this lever is outwardly curved to provide a lip 19, which permits a person to get hold of the

same, when it is desired to operate the valve 15, for the closing thereof or opening of the same.

The lever 16, near its lip end is formed 5 with a locking lug 20, which is adapted to enter and engage in a socket 21, correspondingly shaped thereto and formed in the bottom of the casing 5, centrally of the portion 10 thereof, so that the lever will be locked 10 when the valve 15, is open, to prevent the accidental closing of the same or the easy tampering therewith.

It will be apparent that should the water 15 pass through a meter for registering the quantity used and by excessive pressure of the water the meter is registering more than is being actually used, the valve 15 can be adjusted to reduce the flow of water to the faucet and thereby obviate the same.

20 From the foregoing it is thought that the construction and operation of the faucet will be clearly understood and therefore a more extended explanation has been omitted.

It is of course to be understood that the 25 invention is not restricted to the precise construction and arrangement shown and spe-

cifically described, as variations and modifications may be made, as come properly within the scope of the claim hereunto appended.

What is claimed is:

The combination with a faucet having a body provided with stem and plug valves, of a projection at the end of the plug valve, a resilient lever having a contour corresponding substantially to the shape of the exterior surface of the body to lie in close proximity thereto, and having a slotted end engaged with the projection, the said body being formed with a recess, a protuberance on the inner side of the lever near its free end and correspondingly shaped to the recess for locking engagement therein under the resiliency of the said lever, and a handle on the stem of the other valve and located on the side of the body diametrically opposite the lever.

In testimony whereof, I affix my signature, in presence of two witnesses.

CHARLES M. HOFFMAN.
